UNITED STATES PATENT OFFICE

CARL D. BROWN, OF HOPEDALE, MASSACHUSETTS, ASSIGNOR TO DRAPER CORPORATION,
OF HOPEDALE, MASSACHUSETTS, A CORPORATION OF MAINE

WHIP ROLL RELEASE FOR LOOMS

Application filed June 30, 1931. Serial No. 547,816.

Looms are universally provided with an element extending across the warp sheet between the warp beam and the front of the loom and yieldingly pressed against and deflecting the warp sheet so as to equalize the tension in the warps during the weaving operation. Such an element is usually embodied in what is known as a whip roll. While such an element is necessary to the proper weaving of the cloth in a loom and functions advantageously and efficiently so long as the loom is running, it frequently produces an injurious effect if it remains in pressure-exerting position when the loom is not running. If the loom is left standing even for a short time, as during a pickout or for a longer time, as when the loom is stopped overnight or over a week-end, the pressure imposed by such an element as the whip roll upon and deflecting the warp sheet, particularly where rayon and such fibres are employed, acts to produce stretching and a more or less permanent set in the warps and to leave a mark in the finished woven cloth. The stretching of the warps and the marking of the cloth thus effected is highly undesirable and frequently destroys the commercial value of long pieces of cloth or renders them salable only as seconds. In a companion application of Draper and Kearsley, Serial No. 547,818, filed June 30, 1931, manually operated means are provided enabling the operator, whenever the loom is stopped for any reason, to release the pressure exerted by the element, such as the whip roll, and to induce the movement of this element away from the warp sheet whereby any such defects in the cloth are avoided.

The object of the present invention is to provide manually operated means for a similar purpose acting to secure the desired result by moving the element itself, such as the whip roll, to a position where its pressure on the warp sheet is released.

More specifically the invention has for its object to provide manually operated means for a similar purpose in connection with a whip roll journaled in arms projecting from a whip roll shaft and also in connection with such a whip roll construction wherein the

whip roll shaft is mounted to slide on the loom frame.

The object of the invention is further to provide means acting to stop the loom immediately if the loom is started with the whip roll or other similar element in pressure released position.

These and other objects and features of the invention will appear more fully from the accompanying description and drawings and will be particularly pointed out in the claims.

Since the invention relates to but one feature of a loom and since the general construction and operation of looms are well known and familiar to those skilled in the art, it is only necessary here to illustrate and describe those features with which a preferred embodiment of the invention is particularly concerned.

In the drawings:

Fig. 1 is a top plan view of a portion of the rear end of a loom sufficient to illustrate a simple and preferred embodiment of the invention.

Fig. 2 is a side elevation of the construction shown in Fig. 1.

Only a portion of one of the side frames 1 and only the construction at one side of the loom is shown. It will be understood that the construction at the opposite side is the same so far as the mounting and journalling of the various shafts and parts are concerned.

In this type of construction the whip roll shaft 2 is journaled at each end in a bearing in a block 3 mounted to slide forward and rearward of the loom on the slightly inclined guide plate 4 projecting from the side frame of the loom. This whip roll shaft has adjustably secured thereto at each end, as by a set screw 5, a rearwardly projecting arm 6. The whip roll 7 has its trunnions 8 journaled in these arms. The whip roll shaft 2 has secured thereto the usual downwardly projecting arm indicated in dotted lines 9 by which the whip roll shaft is connected to a suitable let-off mechanism. The action of these let-off mechanisms being well known and familiar, it is unnecessary to illustrate or describe them, but it will be remembered that through the usual connec-

tions therewith the arm such as 9 holds the whip roll shaft so as to cause the whip roll to press yieldingly against and deflect the warp sheet in its passage from the warp beam to the front of the loom and that in turn the bodily movement of the whip roll in its effort to maintain a uniform tension in the warps is utilized to control the action of the let-off mechanism.

10 In the particular construction illustrated, each trunnion 8 of the whip roll is journalled in a bearing block 10 mounted to slide longitudinally in the arm 6 and this bearing block is yieldingly pressed rearwardly by a spring 11.

In the preferred embodiment of this invention an operating shaft 12 is journalled in the loom frame in parallelism with the whip roll shaft and forward thereof. A toggle connection is provided between the whip roll shaft and this operating shaft. This toggle connection is shown as comprising a bifurcated arm 13 journalled on the shaft 2 and an arm 14 secured by the set screw 15 to the shaft 12 with its free end projecting between the bifurcations of the arm 13. The free ends of the arms 13 and 14 are pivoted together by the pivotal connection 16.

30 An operating handle 17 is secured to one end of the shaft 12 by means of which the shaft may be rotated or oscillated between a position in which the whip roll is held in normal working position and a position in which the whip-roll is released from tension-applying position on the warp sheet. The parts are shown in the drawings in full lines in the former position, a position which may be determined by engagement of the arm 13 with a lug 18 projecting from the loom frame. The parts are shown in the second position in dotted lines in Fig. 2 and this position is determined by engagement of the bearing block 3 with an adjustable stop shown as a set screw 19 threaded into and projecting from the loom frame above the guide plate 4.

With the parts in normal position, the whip roll is held yieldingly against the warp sheet and acts in the usual manner to maintain the required tension in the warp sheet. In this position the toggle connection is straightened out, thus locking the bearings for the whip roll shaft against movement on the guide plates 4.

50 If the loom is stopped and left standing even for short periods as during a pick-out, and particularly for longer periods, as overnight or for a week-end, the pressure of the whip roll against the warp sheet acts to produce a permanent set in the warps and unduly to stretch the warps, particularly in the case of delicate yarns and yarns of rayon which take a permanent set when stretched.

65 The present invention enables the operator

readily to prevent this happening with its consequent injury to the cloth.

With the present construction, when the loom is stopped, the operator seizes the handle 17 and throws it forward, thus rotating the shaft 12, breaking the toggle connection and causing the whip roll shaft 2 and its bearing blocks 3 to be slid forward until the bearing blocks engage the stop 19. This operation moves the whip roll and the springs or other yielding means forcing the whip roll against the warp sheet bodily in a direction away from the warp sheet and to a position where the pressure of the whip roll on the warp sheet is removed and thus the tension on the warps released. Owing to the toggle type of connection employed, there is no tendency of the whip roll to return to its operative position and it is necessary for the operator to rotate the handle back to its normal position in order for the whip roll again to be rendered operative in its pressure-exerting position.

96 There is thus presented a very simple and effective means by which the operator may manually and positively shift the whip roll when the loom is stopped to a position where it can exert no pressure on the warp sheet. Thus all danger of injury to the warps or defects in the cloth due to the loom standing with the whip roll pressing against the warp sheet is obviated.

96 The present invention presents a further feature in that it provides means for preventing the loom being started and operated with the whip roll in pressure released position which might happen through oversight on the part of the operator. For this purpose the invention makes use of one of the loom stopping means with which looms are commonly provided. The invention provides means which acts when the whip roll is moved to inoperative pressure-releasing position to render this loom stopping means active so that if the loom is started with the whip roll in pressure releasing position, it will immediately be stopped by the action of the loom stopping means.

100 The particular loom stopping means here illustrated is a warp stop motion of a familiar type indicated generally at 20. In this mechanism the warps support drop wires 21 mounted over relatively endwise reciprocating serrated bars 22. If a warp breaks, its drop wire falls and locks the corresponding serrated bars 22 against relative reciprocation and this event is utilized to stop the loom all in a well known and familiar manner.

105 In the present invention an element such as a finger 23 is secured to the whip roll shaft 2 and projects rearwardly therefrom. Normally this finger stands in a position such as shown in full lines in the drawings. But when the operator shifts the operating handle 17 and moves the parts to the position 110

shown in dotted lines in Fig. 2, the rotary movement and bodily forward movement of the whip roll shaft 2 causes the end of this finger 23 to engage the serrated bars 22 in the same way that a fallen drop wire would engage these bars, thus rendering the warp stop motion active to stop the loom. The loom when the handle 17 is thus moved is, of course, already stopped. But if later on the operator starts the loom without returning the handle 17 and consequently the whip roll and the finger 23 to normal position, the loom will immediately be stopped through the action of the warp stop motion because the finger 23 will be functioning in the same manner as the fallen drop wire.

Having thus described the invention, what is claimed as new, and desired to be secured by Letters Patent, is:

1. In a loom a whip roll shaft, arms extending therefrom, a whip roll journalled in said arms, means associated therewith acting yieldingly to press the whip roll against the warp sheet after it leaves the warp beam, an operating shaft, a handle for manually rotating the operating shaft, and a connection between the said shafts acting when the operating shaft is in one rotary position to maintain the whip roll in its operative position to equalize the tension in the warps during the weaving operation and, when the operating shaft is in another rotary position to retain the whip roll in a position where the tension in the warps is released.

2. In a loom having the construction defined in claim 1, a loom stopping means, and means controlled by the movement of the operating shaft to its second position to render the loom stopping means active to stop the loom immediately if started with the whip roll in released position.

3. In a loom having the construction defined in claim 1, a warp stop motion controlled by drop wires, and an element operated by the movement of the operating shaft to its second position to have the same effect on the warp stop motion as a fallen drop wire, thereby to cause the loom to be stopped immediately if started with the whip roll in released position.

4. In a loom, a whip roll, springs associated with the whip roll normally acting yieldingly to press the whip roll against the warp sheet after it leaves the warp beam to equalize the tension in the warps during the weaving operation and manually operated means for bodily moving the whip roll to a position where the tension in the warps is released.

5. In a loom, a whip roll shaft, arms extending therefrom, a whip roll journalled in said arms, bearings for the whip roll shaft mounted to slide on the loom frame, an operating shaft journalled in the loom frame in parallelism with the whip roll shaft, a toggle connection between said shafts normally act-

ing to hold the bearings and the whip roll in working position, and means for manually rotating the operating shaft to break the toggle connection and slide the bearings on the loom frame to move the whip roll to a position where its pressure on the warp sheet is released.

6. In a loom, an element extending across the warp sheet between the warp beam and the front of the loom yieldingly pressed against and deflecting the warp sheet to equalize the tension in the warps during the weaving operation, manually operated means for moving the said element to a position to release its pressure on the warp sheet, loom stopping means, and means controlled by the movement of said element to its releasing position to render the loom stopping means active to stop the loom immediately if started with the said element in released position.

7. In a loom, an element extending across the warp sheet between the warp beam and the front of the loom, means acting yieldingly to press the said element against and to deflect the warp sheet to equalize the tension in the warps during the weaving operation, manually operated means for shifting bodily both the said element and the said yieldingly acting means in a direction away from the warp sheet and to a position in which the warp sheet is released from the pressure of the said element, loom stopping means, and means controlled by the shift of the said element to pressure releasing position to stop the loom immediately if started with the said element in pressure releasing position.

8. In a loom, an element extending across the warp sheet between the warp beam and the front of the loom, yieldingly pressed against and deflecting the warp sheet to equalize the tension in the warps during the weaving operation and manually operated means for moving the said element to a position to release its pressure on the warp sheet.

9. In a loom, an element extending across the warp sheet between the warp beam and the front of the loom, means acting yieldingly to press the said element against and to deflect the warp sheet to equalize the tension in the warps during the weaving operation, and manually operated means movable to shift the said element bodily away from its normal pressure exerting position, thereby to release the tension in the warps.

10. In a loom, an element extending across the warp sheet between the warp beam and the front of the loom, means acting yieldingly to press the said element against and to deflect the warp sheet to equalize the tension in the warps during the weaving operation, and manually operated means movable in one direction to shift the said element bodily away from its normal pressure exerting position, thereby to release the tension in the warps, and movable in the opposite direction

to shift the said element bodily back to its said normal position.

11. In a loom, an element extending across the warp sheet between the warp beam and

5 the front of the loom, means acting yieldingly to press the said element against and to deflect the warp sheet to equalize the tension in the warps during the weaving operation and manually operated means for shifting

10 bodily both the said element and the said yieldingly acting means in a direction away from the warp sheet and to a position in which the warp sheet is released from the pressure of the said element.

15 12. In a loom, an element extending across the warp sheet between the warp beam and the front of the loom, means acting yieldingly to press the said element against and to deflect the warp sheet to equalize the tension

20 in the warps during the weaving operation and manually operated means for shifting bodily both the said element and the said yieldingly acting means in a direction away from the warp sheet and to a position in which

25 the warp sheet is released from the pressure of the said element and for shifting bodily both the said element and the said means in the opposite direction to restore them to normal position.

30 In testimony whereof, I have signed my name to this specification.
